No. 728,352.

PATENTED MAY 19, 1903.

W. F. BANGS.
REVOLVING AXLE.
APPLICATION FILED JULY 14, 1902.

NO MODEL.

Fig. 1.

UNITED STATES PATENT OFFICE.

WILLIAM F. BANGS, OF BATON ROUGE, LOUISIANA.

REVOLVING AXLE.

SPECIFICATION forming part of Letters Patent No. 728,352, dated May 19, 1903.

Application filed July 14, 1902. Serial No. 115,572. (No model.)

To all whom it may concern:

Be it known that I, WILLIAM F. BANGS, a citizen of the United States, residing at Baton Rouge, in the parish of Baton Rouge, State 5 of Louisiana, have invented certain new and useful Improvements in Revolving Axles; and I do hereby declare the following to be a full, clear, and exact description of the invention, such as will enable others skilled in 10 the art to which it appertains to make and use the same.

This invention relates to revolving axles for vehicles; and it has for its object to provide a cheap and simple construction wherein 15 the sections of an axle will rotate freely and independently of each other and in which said sections will be held securely in axial alinement.

A further object of the invention is to provide a construction of this nature wherein 20 the bearings will be efficiently lubricated, other objects and advantages of the invention being understood from the following description.

25 In the drawings forming a portion of this specification, and in which like numerals of reference indicate similar parts in the several views, Figure 1 is a transverse section through a vehicle equipped with the present invention and including a pair of alining axle-sections, parts being shown in elevation. Fig. 2 is a transverse section through one of the boxes of the center bearing. Fig. 3 is a perspective view of the center bearing.

30 Referring now to the drawings, there is shown a vehicle comprising the axletree 5, on which is mounted the bolster 6, that carries the body of the vehicle, and to the axletree 5 are attached the bearing-boxes for the 35 section of the corresponding axle.

There are employed two end bearing-boxes 7 and 8, having cylindrical passages therethrough in which are disposed the sections 9 and 10 of the axle, and on the sides of these 40 boxes are cast or otherwise formed the cups or pockets 11, having covers 12, said cups or pockets being arranged to receive a lubricant which passes from the pockets to the bearing-surface of the box. It will be understood, of 45 course, that these cups or pockets may contain waste, if desired.

To hold the boxes 7 and 8 to the tree 5, said

boxes have the loops or bands 7' formed thereon and through which are engaged the reduced ends of the axletree. In addition to 55 these loops or bands may be employed bolts 13, engaged through the boxes and the tree, as illustrated.

The center bearing comprises two boxes 14 and 15, having alining passages 16 and 17 therethrough, which are cylindrical and which are in axial alinement with the passages of the boxes 7 and 8. The boxes 14 and 15 are connected by the rigid web 18, which is cast integral with the boxes, so that the latter are 60 held securely from displacement with respect to each other.

On the sides of the boxes 14 and 15 are cast 65 cups 19 and 20 to receive lubricants, these cups having ducts leading therefrom to the bearing-surfaces of the boxes and having covers to prevent ingress of foreign matter.

To hold the boxes 14 and 15 to the axletree, bolts 22 may be engaged therethrough and through the axletree, or clips may be 70 passed around the boxes.

After the boxes have been secured in place in the manner above described the axle-section 9 is engaged with the boxes 7 and 14, while the axle-section 10 is engaged with the 75 boxes 8 and 15. The axle-sections have flanges 24 and 25 near to their outer ends, and beyond these flanges are disposed the hubs 26 and 27 of wheels. On the inner ends of the hubs are disposed plates 35, having 80 pins 36, which engage the hubs and prevent rotation of the plates, and in the outer faces of the plates are angular recesses 37, in which are received the angular flanges 24 25 of the shaft-sections. Against the outer ends of the 85 hubs are disposed plates 39, which are held against rotation by the pins 40, that engage the hubs. Nuts 28 are screwed onto the 90 threaded ends of the axle-sections and impinge against the plates 39 and clamp the 95 hubs firmly to the axle-sections. As the axle-sections rotate the inner faces of the flanges 24 and 25 thereof bear against the outer ends of the boxes 7 and 8 to limit the movement of the wheels toward each other, and to prevent separation of the wheels the inner ends of the axle-sections are passed entirely through the boxes 14 and 15 and have washers 30 and 31, which bear against the inner faces of the 100

said boxes. Pins 32 and 33 are engaged through the inner ends of the axle-sections and prevent dislodgment of the washers. By putting in different washers or adding to the 5 number of washers the axles may be drawn inwardly to compensate for wear, and by tapering the axle-sections in the directions of their inner ends they may be adjusted to compensate for wear between them and the bearing-faces in the boxes.

It will be understood that in practice modifications of the specific construction shown may be made and that any suitable materials and proportions may be used for the various 15 parts without departing from the spirit of the invention.

What is claimed is—

In a vehicle, the combination with an axle-tree having reduced ends, of bearing-boxes

disposed against the under faces of the ends 20 of the axletree and having upwardly-directed loops in which the reduced portions of the tree are received, said boxes having also bolts engaged with their inner end portions and connected with the tree, a pair of intermediate bearing-boxes having a connecting-web 25 at their under sides with which they are integral, axle-sections engaged each with an end bearing-box and the adjacent inner bearing-box and having means for holding them 30 against outward movement, and wheels fixed to the axle-sections beyond the bearing-boxes.

In testimony whereof I affix my signature in presence of two witnesses.

WILLIAM F. BANGS.

Witnesses:

L. E. DROZ,
MARC. T. CARPENTER.
